[57] CLAIM

The ornamental design for a hockey net insert, as shown and described.

DESCRIPTION

FIG. 1 is a perspective view of a hockey net insert, showing my new design;

FIG. 2 is a top view of the design of FIG. 1;

FIG. 3 is a front view of the design of FIG. 1, the rear view being identical;

FIG. 4 is a bottom view of the design of FIG. 1; and,

FIG. 5 is a side view of the design of FIG. 1.

The broken line showing of a hockey net in FIG. 1 is for illustrative purposes only and forms no part of the claimed design.
